UNITED STATES PATENT OFFICE.

NATHANIEL FROST, OF BLOOMINGTON, ILLINOIS.

WATER-CLOSET.

No. 921,393.

Specification of Letters Patent.

Patented May 11, 1909.

Application filed October 16, 1908. Serial No. 457,971.

To all whom it may concern:

Be it known that I, NATHANIEL FROST, a citizen of the United States, and a resident of Bloomington, in the county of McLean 5 and State of Illinois, have invented a new and improved Water-Closet, of which the following is a full, clear, and exact description.

The purpose of the invention is to provide 10 a novel and direct-acting valve of simple and durable construction, automatically operated by the raising and lowering of the closet seat, water being received in a tank from a source of supply when the seat is 15 pressed down, and released from said tank to flush the bowl when the seat is free from pressure.

Another purpose of the invention is to improve upon the construction of water 20 closet valves shown and described in Letters Patent granted to me August 20, 1907, No. 863,977, to the extent that the valve is materially simplified and is made to automatically establish communication between 25 a source of water supply and a storage tank, when the closet is occupied, and wherein, when the closet is unoccupied, the supply of water to the storage tank is cut off and the water stored in said tank is freed, for flushing 30 purposes.

The invention consists in the novel construction and combination of the several parts, as will be hereinafter fully set forth, and pointed out in the claims.

Reference is to be had to the accompanying drawings forming a part of this specification, in which similar characters of reference indicate corresponding parts in all the figures, and in which—

Figure 1 is a vertical section through a water-closet bowl, the improved valve and the flushing tank, illustrating the valve in position to admit of flushing the bowl; Fig. 2 is an enlarged transverse section through 45 the valve mechanism, taken practically on the line 2—2 of Fig. 3; Fig. 3 is an enlarged vertical section through a portion of a closet bowl and a section through the valve mechanism and tank, illustrating the position of 50 the valve mechanism when the closet seat is under pressure, water being admitted to the storage tank but cut off from the bowl; and Fig. 4 is an enlarged vertical detail section taken practically on the line 4—4 of Fig. 3.

A represents a water-closet bowl of any desired character, the particular bowl illus-

trated being provided with a vent chamber 10, that receives water from a source of supply and delivers the same to the bowl A, when required, but the valve mechanism to 60 be described may be applied to any type of bowl.

The valve mechanism is operated through the medium of a hinged seat B, normally held from contact with the bowl A by a 65 spring hinge B' or springs of any suitable character. As is illustrated in Fig. 1, the said seat B is provided with a downwardly-extending finger 11, that operates upon the valve rod or stem, to open the valve to a 70 storage tank, when the seat is occupied, and which, when the seat is unoccupied, permits the valve to cut off communication between the source of water supply and the tank, and to establish communication between the 75 tank and the water-closet bowl for flushing purposes, the latter position being shown in Fig. 1, and the former position in Fig. 3.

The valve casing C extends into the bowl A through the vent 10 in the construction 80 shown, and out beyond the rear of the bowl. This valve casing is preferably made in three sections, an inner section 12, an outer section 13, and an intermediate section 14.

The inner valve section 12 is tapering, being 85 smallest at its inner end, and extends from a point outside of the bowl through the vent chamber 10 into the bowl proper. The said inner valve section 12 is held in place by screwing thereon nuts 15 and 16, the nut 90 15 being shown as engaging the inner wall of the vent chamber 10, and the nut 16 as engaging the outer face of the bowl; but other or equivalent means may be employed for securing said section in place. The said 95 inner section 12 of the valve casing is provided within the vent chamber 10, with a series of outlet openings 17 since the valve casing C is closed at its inner and outer ends; and the said vent chamber 10 is provided with an opening 18, through which 100 water received in the vent chamber is delivered to the bowl A.

At the outer or larger end of the inner casing section 12, a flange 19 is formed, that 105 receives a union 20, having a suitable packing 21, and said union connects the inner casing section 12 with the intermediate casing section 14. The outer casing section 13 has preferably a threaded connection 22 110 with the intermediate casing section 14, and is provided at its outer end with a remov-

able plug 23, having a chamber 24 therein, as is best shown in Fig. 3.

The intermediate section 14 of the valve casing C is of uniform diameter to that of the outer and larger end of the inner section 12, and is provided at each side of its center with a partition, designated as 25 and 26.

A valve stem or rod C' passes through the 10 valve casing C, and that portion 27 of said rod that passes through apertures 28 in the partitions 25 and 26 is rectangular in cross section, so that the rod is held from turning; and between the partitions 25 and 26,

15 apertures or openings 29 are made in the upper and lower portions of the intermediate casing section 14. These openings 29 are in direct communication with the neck D of a tank D', of any desired shape, and said neck

20 surrounds said intermediate casing section 14, as is shown in Fig. 3. The neck D of the tank D' is held in place by means of a nut 30 screwed upon the central casing section 14 near one end and a flange 31 formed

25 at its opposite end. A third partition 32 is formed in the intermediate casing section 14, between the partition 26 and the outlet end of said section, and in this partition 32, a large sized opening 32a is made.

30 A rubber gasket 33 is located at the outer face of the partition 25, having a suitable opening therein corresponding to the opening 28 in said partition, and said gasket constitutes a valve seat, and a corresponding 35 washer or gasket 34 engages the inner face of the partition 32, having a corresponding opening, as is shown in Fig. 3, and this latter gasket constitutes a second valve seat. The washers or gaskets 33 and 34 may be 40 made of any elastic or yielding material.

The stem or rod C' is provided preferably with an integral valve 35, adapted to seat itself at the opening in the gasket 34, and a second valve 36 is screwed or otherwise detachably located on said rod or stem adjacent to its outer end, adapted to seat itself at the opening in the outer gasket 33, as is shown best in Figs. 1 and 3.

45 A spring 37 is coiled around the outer end portion of the valve stem or rod C', having bearing thereon at one end and against the cap nut 23 at its opposite end entering the chamber 24 in said nut.

The seat B, being unoccupied, the spring 55 37 acts to close the valve 36 and open the valve 35, cutting off the supply of water to the tank D', and permitting the water to flow from the tank to the bowl A, as is shown in Fig. 1.

60 Water is received in the outer section of the valve casing C through a pipe 38, connected with any source of water supply, and at the inner end of the valve stem or rod C', a roller 39 is located, that is engaged by the 65 finger 11, when the seat is occupied, as is

illustrated in Fig. 3; and at such time the valve rod or stem is forced outward, seating the valve 35 and unseating the valve 36, and thus, communication between the tank and bowl is cut off and communication between the tank and source of water supply is established.

It will be observed that the water pressure on the valve 36 assists the spring 37 in seating said valve. It will also be understood that the valves are metallic, while the seats are made of rubber or similar substance, which is an opposite arrangement from that usually adapted.

One of the particularly novel features of 80 the invention resides in the neck D of the tank D', surrounding the inlet valve and its seat, and also surrounding the intermediate or main portion of the valve casing C, with the result that, should there be any leakage 85 in the valve casing, the leakage will be within the tank D', and will therefore not prove a nuisance. This arrangement also tends to economy in construction.

Having thus described my invention, I 90 claim as new and desire to secure by Letters Patent:—

1. In a flushing valve for water closets, a valve casing having an inlet chamber, an outlet chamber and an intermediate chamber, a receptacle, communicating with the intermediate chamber, a source of water supply connected with the inlet chamber, apertured partitions in the intermediate chamber, valve seats carried by said partitions, a member movable in the casing, valves carried by said member for engagement with said valve seats, and means for operating the said valve-carrying member, to supply said receptacle and discharge the 105 same.

2. In a flushing valve for water closets, a valve casing having an inlet chamber connected with a water supply, an outlet chamber connected with the closet bowl, and an intermediate chamber having an inlet communicating with the inlet chamber and an outlet communicating with the outlet chamber, a tank having a neck surrounding the intermediate chamber, the said intermediate 110 chamber being in direct communication with said neck, means for holding the neck of the tank in place on said intermediate chamber, a tension-controlled rod slidable in the casing, and valves carried by said rod and controlling the inlet and outlet of said intermediate chamber.

3. In flushing valves for water-closets, a valve casing having an inlet and an outlet, a tension-controlled rod slidable in the casing, a tank having a neck surrounding said inlet and outlet, a flange on the valve casing engaging the neck of the tank at one side thereof, a nut screwing on the valve casing and engaging the opposite side of the neck 120

- to hold the neck of the tank in place, and valves carried by the said rod adapted in the movement of the rod to admit water to the tank or discharge water therefrom.
5. 4. In flushing valves for water closets, a horizontally arranged valve casing having an inlet section connected with a water supply, an outlet section communicating with the closet bowl, an intermediate section having openings in its upper and lower portions, a tank surrounding said intermediate section and communicating with the interior thereof through said openings, the said intermediate section having openings communicating with the inlet and outlet sections, a spring controlled member slideable in the casing, and valves carried by the said member and controlling the openings connecting the intermediate section of the casing with the inlet and outlet sections, the said valves being adapted in the movement of said valve-carrying member to admit water through the intermediate section of the casing to the tank, or discharge water from the tank through the intermediate section to the outlet section.
10. 5. In flushing valves for water closets, a valve casing having an inner chamber connected with the closet bowl, an outer chamber, a source of water supply connected with the outer chamber, an intermediate chamber having partitions provided with openings communicating respectively with the outer and inner chambers, valve seats at said openings, a tank communicating with the interior of said intermediate chamber between the said partitions, a valve carrier the valves of which are adapted for alternate engagement with said valve seats to open and close communication between said water supply and the intermediate chamber, and the said intermediate chamber and the inner chamber, and means for operating the valve carrier by the depression and release of the seat of the closet to which the device is applied.
15. 6. In a flushing valve for water closets, a valve casing having an inlet chamber connected with a water supply, an outlet chamber connected with a closet bowl, and an intermediate chamber provided with apertured partitions, yielding valve seats carried by said partitions, a tank communicating with the intermediate chamber between the said partitions, a spring controlled rod slideable in said valve casing, and valves carried by said rod and adapted for alternate engagement with said valve seats.
20. 7. In a water closet, a bowl, a hinged seat therefor, a valve casing introduced into the bowl, having three chambers on a horizontal plane, one chamber being connected with the bowl and another with a source of water supply, and a tank that receives the intermediate chamber, surrounding the same, all of said chambers being connected, apertured partitions in the said intermediate chamber, yielding valve seats sustained by said partitions, a tension-controlled rod within the casing, means for operating the said rod by the movement of said seat, and valves carried by said rod and adapted for alternate connection with said seats, to establish communication between the water supply and tank, or to seal such communication between the tank and the closet bowl.
25. 8. In a water closet, a bowl, a hinged seat therefor, a valve casing having an inlet section, an outlet section, and intermediate section, the inlet section being connected with a water supply, and the outlet section tapering toward its inner end and provided with a series of outlet openings communicating with the closet bowl, a tank surrounding the intermediate section and communicating with the interior thereof, apertured portions in the intermediate section, establishing communication between said intermediate section and the inlet and outlet sections, the said partitions being provided with valve seats, a spring pressed valve rod within the casing operated by the movement of the seat, and valves carried by said rod and adapted for alternate engagement with said seats.
30. 9. In testimony whereof I have signed my name to this specification in the presence of two subscribing witnesses.
